DOWNHOLE PERFORATING TOOL
SYSTEMS AND METHODS

TECHNICAL FIELD

The present disclosure describes apparatus, systems, and methods for a downhole perforating tool.

BACKGROUND

Hydrocarbon production, such as production of oil and gas, from subterranean reservoirs often utilize perforating tools to create perforations in a casing to enhance production. For instance, some operations in drilling and workover wells utilize running perforation guns into a wellbore to provide effective flow communication between a cased wellbore and productive reservoir. However, a limitation of perforation guns and tools used to operate such guns is the ability to control or isolate a flow of hydrocarbons into the wellbore once the perforations are made.

SUMMARY

In an example implementation, a downhole perforation tool includes an upper sub-assembly configured to couple to a downhole conveyance within a wellbore that is formed from a terranean surface toward a subterranean formation; a plurality of perforation sub-assemblies, where each perforation sub-assembly includes one or more perforation guns, and one or more ports configured to fluidly couple the wellbore with a bore that extends from the one or more ports to the upper sub-assembly; a main wellbore seal positioned between the upper sub-assembly and the plurality of perforation sub-assemblies, the main wellbore seal actuatable to anchor the downhole perforation tool to a casing in the wellbore; and at least one secondary wellbore seal positioned between adjacent perforation sub-assemblies of the plurality of perforation sub-assemblies, the at least one secondary wellbore seal actuatable to fluidly isolate a portion of an annulus of the wellbore from another portion of the annulus of the wellbore.

In an aspect combinable with the example implementation, the plurality of perforation sub-assemblies include at least three perforation sub-assemblies.

In another aspect combinable with any of the previous aspects, the at least one secondary wellbore seal includes a first secondary wellbore seal positioned between a first pair of the at least three perforation sub-assemblies and a second secondary wellbore seal positioned between a second pair of the at least three perforation sub-assemblies.

In another aspect combinable with any of the previous aspects, each of the one or more perforation guns are configured to activate based on an activation signal provided by a stinger tool run into the wellbore.

In another aspect combinable with any of the previous aspects, each perforation sub-assembly includes one or more port covers configured to move between a first position such that the one or more ports is open to the wellbore to fluidly couple the wellbore with the bore and a second position such that the one or more ports is closed to the wellbore to fluidly decouple the wellbore from the bore.

In another aspect combinable with any of the previous aspects, the one or more port covers are configured to move from the first position to the second position based on engagement of one or more sleeves that abuts the one or more port covers with the stinger tool to move the one or more sleeves toward the one or more ports.

2

In another aspect combinable with any of the previous aspects, the one or more port covers is biased toward the first position by one or more springs.

In another aspect combinable with any of the previous aspects, the one or more sleeves includes a profile configured to engage a key on the stinger tool.

In another aspect combinable with any of the previous aspects, the key on the stinger tool is biased by a spring to engage the profile.

10 In another aspect combinable with any of the previous aspects, the one or more secondary wellbore seals includes a packer.

In another aspect combinable with any of the previous aspects, the main wellbore seal includes an inflatable packer.

15 In another example implementation, a method includes running a downhole perforation tool into a wellbore formed from a terranean surface toward a subterranean formation on a downhole conveyance coupled to an upper sub-assembly

20 of the downhole perforation tool, where the downhole perforation tool includes a plurality of perforation sub-assemblies. Each perforation sub-assembly includes one or

more perforation guns, and one or more port. The method further includes positioning the downhole perforation tool at a particular depth in the wellbore with the downhole conveyance; actuating a main wellbore seal positioned between the upper sub-assembly and the plurality of perforation sub-assemblies to anchor the downhole perforation tool to a casing in the wellbore at the particular depth; activating the

30 one or more perforation guns to form one or more perforations in the casing; actuating at least one secondary wellbore seal positioned between adjacent perforation sub-assemblies of the plurality of perforation sub-assemblies to fluidly isolate a portion of an annulus of the wellbore from another portion of the annulus of the wellbore; and receiving a flow of a hydrocarbon fluid through the one or more ports and into a bore that extends from the one or more ports to the upper sub-assembly.

40 In an aspect combinable with the example implementation, the plurality of perforation sub-assemblies include at least three perforation sub-assemblies, and the at least one secondary wellbore seal includes a first secondary wellbore seal positioned between a first pair of the at least three perforation sub-assemblies and a second secondary wellbore seal positioned between a second pair of the at least three perforation sub-assemblies.

45 Another aspect combinable with any of the previous aspects further includes actuating the first and second secondary wellbore seals; and receiving the flow of the hydrocarbon fluid through the one or more ports of each of the at least three perforation sub-assemblies into the bore.

50 In another aspect combinable with any of the previous aspects, activating the one or more perforation guns includes activating each of the one or more perforation guns are configured to activate based on an activation signal provided by a stinger tool run into the wellbore and coupled to the downhole perforation tool.

55 In another aspect combinable with any of the previous aspects, each perforation sub-assembly includes one or more port covers.

60 Another aspect combinable with any of the previous aspects further includes moving the one or more port covers between a first position such that the one or more ports is open to the wellbore to fluidly couple the wellbore with the bore and a second position such that the one or more ports is closed to the wellbore to fluidly decouple the wellbore from the bore.

In another aspect combinable with any of the previous aspects, moving the one or more port covers includes engaging one or more sleeves that abuts the one or more port covers with the stinger tool; and moving the one or more sleeves toward the one or more ports with the stinger tool to move the one or more port covers from the first position to the second position.

In another aspect combinable with any of the previous aspects, the one or more port covers is biased toward the first position by one or more springs.

In another aspect combinable with any of the previous aspects, engaging the one or more sleeves with the stinger tool includes engaging a profile of the one or more sleeves with a key on the stinger tool.

In another aspect combinable with any of the previous aspects, the key on the stinger tool is biased by a spring to engage the profile.

In another aspect combinable with any of the previous aspects, the one or more secondary wellbore seals includes a packer.

In another aspect combinable with any of the previous aspects, actuating the main wellbore seal includes inflating the main wellbore seal.

Implementations of a downhole perforating tool system according to the present disclosure may include one or more of the following features. For example, a downhole perforating tool system according to the present disclosure can save rig time by allowing a single run to perforate and isolate, rather than using a dedicated perforation run in combination with and using cement for plugging the perforation that requires a rig operator and full cement unit. As another example, a downhole perforating tool system according to the present disclosure can eliminate the use of cement as an isolation mechanism to stop unwanted flow of hydrocarbon production. For example, a downhole perforating tool system according to the present disclosure can provide for isolation in a single perforation stage or section, as well as a multiple perforation stages or sections.

The details of one or more implementations of the subject matter described in this disclosure are set forth in the accompanying drawings and the description below. Other features, aspects, and advantages of the subject matter will become apparent from the description, the drawings, and the claims.

BRIEF DESCRIPTION OF THE DRAWINGS

FIG. 1 is a schematic diagram of a wellbore system that includes an example implementation of a downhole perforation tool according to the present disclosure.

FIGS. 2A-2D are schematic illustrations of a wellbore operation with a downhole perforation tool according to the present disclosure.

FIGS. 3A-3D are schematic illustrations of a downhole perforation tool during the wellbore operation of FIGS. 2A-2D according to the present disclosure.

FIGS. 4A-4D are schematic illustrations of a downhole perforation tool during an operation with a shifting tool stinger according to the present disclosure.

FIGS. 5A-5C are schematic illustrations of a downhole perforation tool during an operation of a valve assembly of the tool according to the present disclosure.

FIGS. 6A-6D are further schematic illustrations of a downhole perforation tool during an operation of a valve assembly of the tool according to the present disclosure.

FIGS. 7A-7B are further schematic illustrations of a downhole perforation tool during an operation of a valve assembly of the tool according to the present disclosure.

DETAILED DESCRIPTION

FIG. 1 is a schematic diagram of wellbore system 10 that includes a downhole perforation tool 100 according to the present disclosure. Generally, FIG. 1 illustrates a portion of one embodiment of a wellbore system 10 according to the present disclosure in which the downhole tool 100, as a downhole perforation tool 100, may be run into a wellbore 20 and activated at a particular downhole position (or positions) within a wellbore tubular within the wellbore 20. 10 Generally, the downhole perforation tool 100 can be activated to selectively fire one or more perforating guns to create perforations in the wellbore tubular in order to fluidly couple an interior volume of the tool 100 (as well as the wellbore) with a subterranean reservoir (or formation) 40. 15 The downhole perforation tool 100 can be further activated to selectively actuate one or more wellbore seals (for example, packers or otherwise) to fluidly isolate a portion of the wellbore 20 from another portion of the wellbore 20. The downhole perforation tool 100 can be further activated to selectively open one or more valve assemblies to fluidly couple the tool 100 (and other production tubular equipment in the wellbore 20) with the subterranean formation 40 to produce one or more hydrocarbon (or other) fluids) to a terranean surface 12. 20

30 In this example, the downhole perforation tool 100 can be connected to a downhole conveyance 55, such as a drill pipe or other work string that is comprised of multiple, threaded tubulars. In some alternative aspects, the downhole conveyance 55 can be a wireline or slickline conveyance. Thus, the downhole perforation tool 100 is connected to the downhole conveyance 55 during a running in process, a running out process, or during an operations of the downhole perforations tool 100 in the wellbore 20.

As shown, the wellbore system 10 accesses the subterranean formation 40 and provides access to hydrocarbons located in such subterranean formation 40. In an example implementation of system 10, the system 10 may be used for a production operation in which the hydrocarbons may be produced from the subterranean formation 40 within a wellbore tubular 35, for example, as production tubing 35. 45 However, the wellbore tubular 35 can be any tubular member positioned in the wellbore 20 such as any type of casing, a liner or lining, or other form of tubular member.

A drilling assembly (not shown) can be used to form the wellbore 20 extending from the terranean surface 12 and through one or more geological formations in the Earth. One or more subterranean formations, such as subterranean zone 40, are located under the terranean surface 12. As will be explained in more detail below, one or more wellbore 55 casings, such as a surface casing 30 and production casing 35, may be installed in at least a portion of the wellbore 20. In some embodiments, a drilling assembly used to form the wellbore 20 may be deployed on a body of water rather than the terranean surface 12. For instance, in some embodiments, the terranean surface 12 may be an ocean, gulf, sea, or any other body of water under which hydrocarbon-bearing formations may be found. In short, reference to the terranean surface 12 includes both land and water surfaces and contemplates forming and developing one or more wellbore systems 10 from either or both locations.

In some embodiments of the wellbore system 10, the wellbore 20 may be cased with one or more casings. As

illustrated, the wellbore 20 includes a conductor casing 25, which extends from the terranean surface 12 shortly into the Earth. A portion of the wellbore 20 enclosed by the conductor casing 25 may be a large diameter borehole. Additionally, in some embodiments, the wellbore 20 may be offset from vertical (for example, a slant wellbore). Even further, in some embodiments, the wellbore 20 may be a stepped wellbore, such that a portion is drilled vertically downward and then curved to a substantially horizontal wellbore portion. Additional substantially vertical and horizontal wellbore portions may be added according to, for example, the type of terranean surface 12, the depth of one or more target subterranean formations, the depth of one or more productive subterranean formations, or other criteria.

Downhole of the conductor casing 25 may be the surface casing 30. The surface casing 30 may enclose a slightly smaller borehole and protect the wellbore 20 from intrusion of, for example, freshwater aquifers located near the terranean surface 12. The wellbore 20 may then extend vertically downward. This portion of the wellbore 20 may be enclosed by the production casing 35. Any of the illustrated casings, as well as other casings or tubulars that may be present in the wellbore system 10, may include one or more casing collars. As shown in FIG. 1, the downhole perforation tool 100 may be run into the wellbore 20. In some aspects, as shown, the downhole perforation tool 100 may be inserted into the wellbore 20, which may be filled with a fluid, such as a drilling fluid or otherwise.

Turning now to FIGS. 2A-2D, these figures schematically illustrate a wellbore operation with the downhole perforation tool 100 according to the present disclosure. FIG. 2A shows the downhole perforation tool 100 as it is run into the wellbore 20 via downhole conveyance (or drill pipe) 55. In FIG. 2A, the downhole perforation tool 100 has been run into the wellbore 20 to a particular depth, such as at a productive subterranean formation that stores one or more hydrocarbon fluids. In FIG. 2A, the downhole perforation tool 100 is an inactivated state in that no wellbore seal, perforating gun, or valve assembly has yet to be actuated.

Turning to FIG. 3A, this figure illustrates the downhole perforation tool 100 in an inactivated state. In this example implementation of the downhole perforation tool 100, an upper sub-assembly 102 comprises a connection (for example, threaded or otherwise) to the downhole conveyance 55 and provides a bore 101 that extends through the downhole perforation tool 100 to allow a flow of a fluid or entry of, for example, a shifting tool to actuate particular components of the downhole perforation tool 100.

Downhole of the upper sub-assembly 102 is a main wellbore seal (or main seal) 104. In some aspects, the main seal 104 comprises an inflatable or other type of main packer 104. The main packer 104, once actuated, can seal a portion of the wellbore 20 from another portion of the wellbore 20 and, generally, provide a setting mechanism to engage the production casing 35 and hold the downhole perforation tool 100 at a particular location within the wellbore 20.

In this example implementation of the downhole perforation tool 100, three perforating sub-assemblies 108a, 108b, and 108c, are positioned in the downhole perforation tool 100 between the main packer 104 and a lower sub-assembly 116. In this example, each perforating sub-assembly 108a, 108b, and 108c include one or more perforating guns 110a, 110b, and 110c, respectively. In this example, each perforating sub-assembly 108a, 108b, and 108c includes four perforating guns 110a, 110b, and 110c, respectively. However, in alternate implementations, more or fewer perforating guns can be positioned in each perforating

sub-assembly. Further, in alternative aspects of the downhole perforation tool 100, more or fewer than three perforating sub-assemblies can be included.

The lower sub-assembly 116, in this example, can be a cap or end to the downhole perforation tool 100. Alternatively, the lower sub-assembly 116 can include a connection (for example, threaded or otherwise) from which further downhole tools can be connected to the downhole perforation tool 100.

10 In the example implementation of FIG. 2A, secondary wellbore seals 106, 112, and 114 are positioned between the main seal 104 and the perforating sub-assembly 108a, between the perforating sub-assembly 108a and the perforating sub-assembly 108b, and between the perforating sub-assembly 108b and the perforating sub-assembly 108c, respectively. Each of the wellbore seals 106, 112, and 114 can be selectively actuated (by pressure, mechanically, or otherwise) to expand and contact the production casing 35. Thus, each perforating sub-assembly 108a, 108b, and 108c 15 can be fluidly isolated (external to the downhole perforation tool 100, within the wellbore 20) from each other perforating sub-assembly 108a, 108b, and 108c based on the selective actuation of one or more of the wellbore seals 106, 112, and 114.

20 Turning to FIG. 2B, this figure shows the downhole perforation tool 100 at the particular position in the wellbore 20 and with the main packer 104 actuated to contact and seal against the production casing 35. For example, once the downhole perforation tool 100 is set at a desired depth in the wellbore 20, the main packer 104 can be actuated to set the downhole perforation tool 100 in place within the production casing 35 (but still connected to the drill string 55). FIG. 3B shows the downhole perforation tool 100 with the main packer 104 actuated. In this example, a setting tool 200 can be run into the wellbore 20 (for example, on the drill pipe 55 or otherwise) to actuate the main packer 104 with a stinger 202. As described more fully later, the stinger 202 can also actuate one or more other components of the downhole perforation tool 100 when desired.

25 Turning to FIG. 2C, this figure shows the downhole perforation tool 100 at the particular position in the wellbore 20 and all of the perforating guns being activated to generate shots 125 to cause perforations in the production casing 35. For example, once the downhole perforation tool 100 is set at the desired depth with the main packer 104 actuated to set the downhole perforation tool 100 in place, the perforating guns (all or a portion) can be actuated. FIG. 3C shows the downhole perforation tool 100 with the main packer 104 30 actuated and perforating guns 110a, 110b, and 110c of their respective perforating sub-assemblies being activated to create shots 125. As shown in this example, the setting tool 200 can generate an activation signal 204 to activate perforating guns 110a, 110b, and 110c. In some aspects, the activation signal 204 can be designed to only activate a 35 portion of the perforating guns, such as only perforating guns 110a, only perforating guns 110b, or only perforating guns 110c (or any combination thereof).

40 Turning to FIG. 2D, this figure shows the downhole perforation tool 100 at the particular position in the wellbore 20 having had all of the perforating guns being activated to generate shots 125 to cause perforations 129 in the production casing 35. For example, once the downhole perforation tool 100 is set at the desired depth with the main packer 104 actuated to set the downhole perforation tool 100 in place and with the perforating guns (all or a portion) actuated, wellbore fluid 127 (such as hydrocarbon fluids) can flow 45 from the subterranean formation, through the perforations

129, and into the wellbore 20 downhole of the main packer 104. The main packer 104 can prevent wellbore fluid 127 from flowing uphole within the wellbore 20 outside of the downhole perforation tool 100 and, instead, the wellbore fluid 127 flows uphole through the downhole perforation tool 100 and into the production casing 35.

FIG. 3D shows the downhole perforation tool 100 with the main packer 104 actuated and perforating guns 110a, 110b, and 110c of their respective perforating sub-assemblies having been activated to create perforations 129. As wellbore fluid 127 flows into the wellbore, the stinger 202 can be removed from the downhole perforation tool 100 and ports 118a, 118b, and 118c on the respective perforating sub-assemblies 108a, 108b, and 108c can be selectively opened to allow the wellbore fluid 127 to enter the bore 101. As shown in this example, the ports 118a, 118b, and 118c of the respective perforating sub-assemblies 108a, 108b, and 108c are positioned close to or aligned with the respective perforating guns 110a, 110b, and 110c. Thus, after discharge of the perforating guns 110a, 110b, and 110c, the ports 118a, 118b, and 118c can be selectively opened to allow the wellbore fluid 127 to enter the bore 101.

FIGS. 4A-4D are schematic illustrations of a downhole perforation tool during the wellbore operation of FIGS. 2A-2D according to the present disclosure. For example, FIGS. 4A-4D show operation of the stinger 202 that is part of the setting tool 200 and how each set of ports 118a, 118b, or 118c can be selectively closed to allow selective production into the bore 101.

FIG. 4A shows an example operation in which, subsequent to discharge of all of the perforating guns 110a, 110b, and 110c, all of the ports 118a, 118b, and 118c are opened to allow the wellbore fluid 127 to enter the bore 101 therethrough. Once the wellbore fluid 127 enters the bore 101, the fluid can travel uphole into the production casing 35 (or other production tubing). As shown in this operation, only the main packer 104 is actuated and set against the production casing 35, thereby forcing all wellbore fluid 127 through the bore 101 of the downhole perforation tool 100.

FIG. 4B shows an example operation in which the ports 118c of the perforation sub-assembly 108c are closed by the stinger 202 of the setting tool 200. In some aspects, for example, the setting tool 200 may be run into the wellbore 20 and actuate a valve assembly in the perforation sub-assembly 108c to close the ports 118c, thereby preventing wellbore fluid 127 from flowing into the ports 118c.

Prior to actuating the valve assembly to close the ports 118c, the wellbore seal 114 can be actuated to expand and seal against the production casing 35. When actuated, the wellbore seal 114 can fluidly decouple a portion of an annulus 103 of the wellbore 20 that is downhole of the wellbore seal 114 from a portion of the annulus 103 of the wellbore 20 uphole of the wellbore seal 114. Wellbore fluid 127 that enters ports 118a and 118b of perforation sub-assemblies 108a and 108b, respectively, travels uphole through the bore 101. However, wellbore fluid 127 within the wellbore 20 uphole of the wellbore seal 114 is forced to enter the ports 118a or the ports 118b.

FIG. 4C shows an example operation in which the ports 118b of the perforation sub-assembly 108b are closed by the stinger 202 of the setting tool 200. In some aspects, for example, the setting tool 200 may be run into the wellbore 20 and actuate a valve assembly in the perforation sub-assembly 108b to close the ports 118b, thereby preventing wellbore fluid 127 from flowing into the ports 118b.

Prior to actuating the valve assembly to close the ports 118b, the wellbore seals 114 and 112 can be actuated to

expand and seal against the production casing 35. When actuated, the wellbore seals 114 and 112 can fluidly decouple a portion of the annulus 103 of the wellbore 20 that is downhole of the wellbore seal 114 and a portion of the annulus 103 of the wellbore 20 uphole of the wellbore seal 112 from a portion of the wellbore 20 that is adjacent the perforation sub-assembly 108b. Wellbore fluid 127 that enters ports 118a and 118c of perforation sub-assemblies 108a and 108c, respectively, travels uphole through the bore 101. However, wellbore fluid 127 may not enter the wellbore 20 adjacent the perforation sub-assembly 108b.

FIG. 4D shows an example operation in which the ports 118a of the perforation sub-assembly 108a are closed by the stinger 202 of the setting tool 200. In some aspects, for example, the setting tool 200 may be run into the wellbore 20 and actuate a valve assembly in the perforation sub-assembly 108a to close the ports 118a, thereby preventing wellbore fluid 127 from flowing into the ports 118a.

Prior to actuating the valve assembly to close the ports 118a, the wellbore seal 112 (and in some aspects, wellbore seal 106) can be actuated to expand and seal against the production casing 35. When actuated, the wellbore seal 112 (in combination with the actuated main packer 104 or the actuated wellbore seal 106, or both) can fluidly decouple a portion of the annulus 103 of the wellbore 20 that is downhole of the wellbore seal 112 from a portion of the annulus 103 of the wellbore 20 that is uphole of the wellbore seal 112. Wellbore fluid 127 that enters ports 118b and 118c of perforation sub-assemblies 108b and 108c, respectively, travels uphole through the bore 101. However, wellbore fluid 127 may not enter the wellbore 20 adjacent the perforation sub-assembly 118a.

FIGS. 5A-5C are schematic illustrations of the downhole perforation tool 100 during an operation of a valve assembly of the tool 100 according to the present disclosure. For example, as described with reference to FIGS. 4A-4D, one or more valve assemblies of the perforation sub-assemblies 108a, 108b, and 108c can be operated to close the ports 118a, 118b, and 118c, respectively. Turning to FIG. 5A, a portion of the downhole perforation tool 100 that includes the perforation sub-assembly 108a is shown (in cross-section). In this example implementation, a valve assembly of the perforation sub-assembly 108a includes one or more port covers 122a and one or more spring assemblies 124a that abut an uphole end of the one or more port covers 122a. In FIG. 5A, the perforation sub-assembly 108a is shown prior to activation of the perforating guns 110a.

Turning to FIG. 5B, the perforation sub-assembly 108a is shown after activation of the perforating guns 110a and opening of the ports 118a. In some aspects, ports 118a are in an open state after activation of the perforating guns 110a (for example, due to initiation of an explosive charge or charges in each perforating gun 110a to expose the ports 118a). As shown in FIG. 2B, the port covers 122a are positioned uphole of the ports 118a, thereby allowing wellbore fluid to enter the ports 118a from the wellbore.

FIG. 5C shows the perforation sub-assembly 108a after operation of the valve assembly to urge the port covers 122a over the ports 118a, thereby preventing wellbore fluid from entering the ports 118a from the wellbore. In this example, a force 126 is applied to the spring assemblies 124a to urge the spring assemblies 124a in a downhole direction (in other words, away from the main packer 104 and toward the ports 118a). As the spring assemblies 124a are urged in the downhole direction, they push the port covers 122a to cover the ports 118a as shown.

Turning to FIGS. 6A-6D, these figures show schematic illustrations of an example operation of the valve assembly described in FIGS. 5A-5C. Like FIGS. 5A-5C, in this example, the operation of the valve assembly of the perforation sub-assembly 108a is described; however, this description could also be applied to valve assemblies of the perforation sub-assemblies 108b and 108c. As shown in FIG. 6A, the stinger 202 can include one or more keys 206 that are configured to fit within matching profiles 130a formed on sleeves 128a positioned within the perforation sub-assembly 108a uphole of spring assemblies 124a (which are positioned uphole of the port covers 122a). As shown in FIG. 6A, the ports 118a are open, and the stinger 202 is being moved in a downhole direction into the perforation sub-assembly 108a (in other words, into the bore 101 of the perforation sub-assembly 108a).

Turning to FIG. 6B, as this figure shows, once the stinger 202 is moved into the perforation sub-assembly 108a a sufficient distance, the keys 206 snap into the profiles 130a, thereby coupling the sleeves 128a with the stinger 202. Turning briefly to FIGS. 7A-7B, these figures further illustrate the coupling of the stinger 202 with the sleeves 128a. For example, as shown, springs 208 within the stinger 202 are positioned to urge the keys 206 radially outward from the stinger 202. As the stinger 202 is moved through the sleeves 128a (as shown in FIG. 7A), the keys 206 eventually reach the profiles 130a. Once the keys 206 reach the profiles 130a, springs 208 urge the keys 206 to snap into the profiles 130a as shown in FIG. 7B. In some aspects, the stinger 202 can pull the keys 206 from the profiles 130a, such as to disengage the stinger 202 from the downhole perforation tool 100.

Turning to FIG. 6C, this figure illustrates the stinger 202 coupled with the sleeves 128a, and the sleeves 128a pushing the port covers 122a down to cover ports 118a. In this example, the sleeves 128a also include profiles 132a that, when aligned with keys 134a formed in the perforation sub-assembly 108a, receive the keys 134a to hold the port covers 122a in position as shown in FIG. 6C. Once the port covers 122a are in place as shown in FIG. 6C, the stinger 202 can be decoupled from the sleeves 128a and, for example, run out of the wellbore 20 as shown in FIG. 6D.

While this specification contains many specific implementation details, these should not be construed as limitations on the scope of any inventions or of what may be claimed, but rather as descriptions of features specific to particular implementations of particular inventions. Certain features that are described in this specification in the context of separate implementations can also be implemented in combination in a single implementation. Conversely, various features that are described in the context of a single implementation can also be implemented in multiple implementations separately or in any suitable subcombination. Moreover, although features may be described above as acting in certain combinations and even initially claimed as such, one or more features from a claimed combination can in some cases be excised from the combination, and the claimed combination may be directed to a subcombination or variation of a subcombination.

Similarly, while operations are depicted in the drawings in a particular order, this should not be understood as requiring that such operations be performed in the particular order shown or in sequential order, or that all illustrated operations be performed, to achieve desirable results. In certain circumstances, multitasking and parallel processing may be advantageous. Moreover, the separation of various system components in the implementations described above should not be understood as requiring such separation in all imple-

mentations, and it should be understood that the described program components and systems can generally be integrated together in a single software product or packaged into multiple software products.

A number of implementations have been described. Nevertheless, it will be understood that various modifications may be made without departing from the spirit and scope of the disclosure. For example, example operations, methods, or processes described herein may include more steps or fewer steps than those described. Further, the steps in such example operations, methods, or processes may be performed in different successions than that described or illustrated in the figures. Accordingly, other implementations are within the scope of the following claims.

What is claimed is:

1. A downhole perforation tool, comprising:
an upper sub-assembly configured to couple to a downhole conveyance within a wellbore tubular installed in a wellbore that is formed from a terranean surface toward a subterranean formation;
a plurality of perforation sub-assemblies, each perforation sub-assembly comprising:
one or more perforation guns configured to initiate an explosive charge, each of the one or more perforation guns configured to activate based on an activation signal provided by a stinger tool run into the wellbore through the wellbore tubular and separately from the upper sub-assembly;
one or more ports configured to fluidly couple the wellbore with a bore that extends from the one or more ports to the upper sub-assembly to receive a wellbore fluid from the subterranean formation, through the one or more ports, and into the bore;
one or more port covers configured to move between a first position such that the one or more ports is open to the wellbore to fluidly couple the wellbore with the bore and a second position such that the one or more ports is closed to the wellbore to fluidly decouple the wellbore from the bore;
for each port cover, a sleeve positioned uphole of the port cover; and
for each port cover, at least one spring positioned between the sleeve and the port cover and to abut an uphole end of the port cover, the spring biased to urge the port cover toward the first position;
a main wellbore seal positioned between the upper sub-assembly and the plurality of perforation sub-assemblies, the main wellbore seal actuatable to anchor the downhole perforation tool to a casing in the wellbore; and
at least one secondary wellbore seal positioned between adjacent perforation sub-assemblies of the plurality of perforation sub-assemblies, the at least one secondary wellbore seal actuatable to fluidly isolate a portion of an annulus of the wellbore from another portion of the annulus of the wellbore.

2. The downhole perforation tool of claim 1, wherein the plurality of perforation sub-assemblies comprise at least three perforation sub-assemblies, and the at least one secondary wellbore seal comprises a first secondary wellbore seal positioned between a first pair of the at least three perforation sub-assemblies and a second secondary wellbore seal positioned between a second pair of the at least three perforation sub-assemblies.

11

3. The downhole perforation tool of claim 2, wherein each of the one or more perforation guns is configured to activate based on an activation signal provided by a stinger tool run into the wellbore.

4. The downhole perforation tool of claim 3, wherein the one or more port covers is configured to move from the first position to the second position based on engagement of the sleeve of one or more sleeves, that abuts the one or more port covers through the spring of one or more springs, with the stinger tool to move the one or more sleeves toward the one or more ports.

5. The downhole perforation tool of claim 4, wherein the one or more sleeves comprises a profile configured to engage a key on the stinger tool.

6. The downhole perforation tool of claim 5, wherein the key on the stinger tool is biased by a spring to engage the profile.

7. The downhole perforation tool of claim 5, wherein the stinger is configured to pull the key from the profile to disengage the stinger tool from the one or more sleeves.

8. The downhole perforation tool of claim 7, wherein the key is one of two keys radially spaced on the stinger tool.

9. The downhole perforation tool of claim 8, wherein the two keys are radially spaced 180 degrees apart on the stinger tool.

10. The downhole perforation tool of claim 3, wherein the one or more secondary wellbore seals comprises a packer.

11. The downhole perforation tool of claim 3, wherein the main wellbore seal comprises an inflatable packer.

12

12. The downhole perforation tool of claim 1, wherein the one or more port covers is configured to move from the first position to the second position based on engagement of the sleeve of one or more sleeves, that abuts the one or more port covers through the spring of one or more springs, with the stinger tool to move the one or more sleeves toward the one or more ports.

13. The downhole perforation tool of claim 12, wherein the one or more sleeves comprises a profile configured to engage a key on the stinger tool.

14. The downhole perforation tool of claim 13, wherein the key on the stinger tool is biased by a spring to engage the profile.

15. The downhole perforation tool of claim 14, wherein the one or more secondary wellbore seals comprises a packer.

16. The downhole perforation tool of claim 15, wherein the main wellbore seal comprises an inflatable packer.

17. The downhole perforation tool of claim 13, wherein the stinger tool is configured to pull the key from the profile to disengage the stinger tool from the one or more sleeves.

18. The downhole perforation tool of claim 17, wherein the key is one of two keys radially spaced on the stinger tool.

19. The downhole perforation tool of claim 1, wherein the one or more secondary wellbore seals comprises a packer.

20. The downhole perforation tool of claim 1, wherein the main wellbore seal comprises an inflatable packer.
